ALBERT GEORG KOECHLIN, OF BASEL, SWITZERLAND, ASSIGNOR TO SPINNEREI & WEBEREI STEINEN A. G., OF STEINEN, GERMANY.

LOOM FOR WEAVING.

1,073,145.

Specification of Letters Patent. Patented Sept. 16, 1913.

Application filed January 18, 1913. Serial No. 742,889.

To all whom it may concern:

Be it known that I, ALBERT GEORG KOECHLIN, a citizen of the Swiss Republic, and resident of Basel, Switzerland, have 5 invented new and useful Improvements in Looms for Weaving, of which the following is a full, clear, and exact specification.

In all looms, whether power looms or hand looms, or whether designed for the 10 weaving of animal or vegetable textile fibers, it is a common practice to divide the warp between the yarn beam and the harness in order to prevent the warp threads becoming entangled or fractured. In the 15 case of most looms there are used for this purpose stationary round or flat lease rods or slats which are inserted into the warp threads so as to divide them into two bands or sets. Such stationary rods or slats, 20 however, possess the disadvantage that they do not perfectly divide the warp threads and frequently cause their breakage, owing to the fact that the warp threads adhere to them and to each other and obviously 25 must rub against said rods or slats to no inconsiderable extent and are thereby weakened and not infrequently torn. In order to obviate these disadvantages, it has already been proposed to employ movable 30 driven lease rods or bars or other automatically reciprocated lease members, but all these automatically driven lease members, though better dividing the warp, have necessarily the disadvantage of a more or 35 less great frictional coöperation with the warp threads. Now, in order to obviate this drawback, I employ according to the present invention for dividing the warp a plurality of freely rotatable rollers arranged 40 in contact with each other and so actuated by means of an automatic drive that they are caused to roll one upon another as well as on the stretched threads. By this means the division of the warp is 45 not only effected much more efficiently than hitherto, but the said division takes place without the slightest friction between the dividers and the warp threads so that the rubbing and the resulting weakening of 50 the latter are completely obviated and the fracture of the threads is so far as possible avoided. These warp dividing rollers can be arranged in the warp between the 55 yarn beam and the back-bearer, or between the latter and the tackle or harness. In

the first case they are movably mounted in lateral slot guides transversely to the warp direction, in such a manner that they can freely follow the gradual inward movement of the warp path due to the decrease 60 of diameter of the yarn beam. The drive can be effected from any suitable shaft of the loom and either continuously or intermittently; in the latter case at more or less larger intervals of time. For increasing 65 their movability the dividing rollers may be mounted in ball-bearings.

The accompanying drawing shows two modes of carrying out the invention.

In the said drawing: Figure 1 is a dia- 70 grammatic cross sectional view of a loom fitted with a warp dividing device of the type first above mentioned. Fig. 2 is a similar view of a loom illustrating the application thereto of the second type of di- 75 viding device, and Figs. 3 and 4 illustrate modifications of details of the device.

Referring first to Fig. 1, there are ar- 80 ranged in the warp between the yarn beam *a* and the back-bearer *b* two rotatable di- viding rollers *c*, *d* having end pivots which are freely movable in bearing forks *e* on lat- 85 eral carrying arms *f*. These two rollers, which are preferably tubular, are in contact with one another and with the threads of the divided warp. The carrying arms *f* are mounted upon a rocking shaft *g* which is periodically oscillated, through the me- 90 dium of an arm *h*, by a cam *i* keyed upon the treadle eccentric shaft *j* in order to move the rollers *c*, *d* to-and-fro along the warp threads. By this movement of the rollers insure the division of the warp; they roll against one another in opposite di- 95 rections and upon the warp threads without friction, so that during this motion of the rollers, which effects the division of the warp, the threads are carefully pre- served.

Figs. 3 and 4 illustrate a suitable mode 100 of mounting the dividing rollers in their fork bearings *e*. In each fork *e* there is movably mounted on balls a slide-block *m* in which the end pins or pivots *n* of the rollers are mounted in ball bearings in the 105 known manner. By this method of mounting the movability of the dividing rollers, both as regards rectilinear and rotary mo- 110 tion is considerably increased.

The construction shown in Fig. 2 differs 110

from that first described essentially in that in this case the dividing rollers *c*, *d* are arranged between the back-bearer and the harness *h* and above one another instead of horizontally adjacent to one another, the said rollers *c* and *d* being oscillated in an approximately horizontal direction by the upwardly directed forked arms *f*.

The actuation of the dividing rollers can 10 be effected from any shaft of the loom through the medium of eccentrics, cams or other suitable devices. The movement of the rollers upon the warp can take place at every pick or only at every second, 15 third or like pick and the rollers, instead of moving in an approximately straight line, can be caused to move through a circular or other path. With dense warp more than two dividing rollers may be 20 made use of, if desired.

What I claim is:

1. In looms for weaving, a warp-dividing device comprising a plurality of freely rotatable dividing rollers in the warp, arranged in contact with each other, and automatic means for causing said dividing rollers to roll frictionless one upon another as well as on the stretched warp threads.
2. In looms for weaving, a warp-dividing device comprising two freely rotatable dividing rollers in the warp, arranged in contact with one another, and automatic means for causing said dividing rollers to roll frictionless one on the other in opposite directions as well as on the stretched warp threads.
3. In looms for weaving, a warp-dividing

device comprising two freely rotatable dividing rollers in the warp, arranged side by side in contact with one another, an automatic periodically operating means for causing said dividing rollers to roll frictionless one on the other and on the stretched warp threads.

4. In looms for weaving, a warp-dividing device comprising two freely rotatable dividing rollers arranged in the warp between the warp beam and the back-bearer, lateral bearing guides for the said rollers arranged so as to allow the same to move transversely to the warp direction, and automatic means connected with said guides for causing the rollers to move along the warp so as to roll frictionless one upon another and on the stretched warp threads, substantially as described.

5. In looms for weaving, a warp-dividing device comprising two freely rotatable dividing rollers, ball bearings for the same, movable carrying members for said ball bearings and automatic means connected with said carrying members for positively causing the rollers to move along the warp so as to roll frictionless one upon the other and on the stretched warp threads, substantially as described.

In witness whereof I have hereunto signed my name this 30th day of December, 1912, in the presence of two subscribing witnesses.

ALBERT GEORG KOECHLIN.
